(57) **CLAIM**

The ornamental design for a multiport for making optical connections, as shown and described.

DESCRIPTION

FIG. 1 is a front perspective view of an embodiment of a multiport for making optical connections showing our new design;

FIG. 2 is a top view thereof of FIG. 1;

FIG. 3 is a bottom view thereof of FIG. 1;

FIG. 4 is a right side view thereof of FIG. 1;

FIG. 5 is a left side view thereof of FIG. 1;

FIG. 6 is a front view thereof of FIG. 1; and,

FIG. 7 is a rear view thereof of FIG. 1.

In FIGS. 1-7, the evenly-spaced broken lines are included for the purpose of illustrating environmental structure and form no part of the claimed design.
